[57] CLAIM

The ornamental design for an electric fillet knife handle, as shown and described.

DESCRIPTION

FIG. 1 is a perspective view of an electric fillet knife handle of the present invention;

FIG. 2 is a right-side elevation view thereof;

FIG. 3 is a left-side elevation view thereof;

FIG. 4 is a top plan view thereof;

FIG. 5 is a bottom plan view thereof;

FIG. 6 is a rear elevation view thereof; and,

FIG. 7 is a front elevation view thereof.

The broken lines showing the blade and handle features in FIGS. 1-7 are for illustrative purposes only and form no part of the claimed design.
